UNITED STATES PATENT OFFICE

157,319

STEP BOX

Thomas C. Bair, Utica, N. Y., assignor to Utica Radiator Corporation, Utica, N. Y., a corporation of New York

Application January 13, 1948, Serial No. 143,711

Term of patent 14 years

(Cl. D15—8)

To all whom it may concern:

Be it known that I, Thomas C. Bair, a citizen of the United States, residing at Utica, county of Oneida, State of New York, have invented a new, original, and ornamental Design for Step Box, of which the following is a specification, reference being had to the accompanying drawings, forming a part thereof.

In the drawings:

Figure 1 is a plan view of a step box, showing my new design,

Figure 2 is a bottom view,

Figure 3 is a front elevational view,

Figure 4 is a side elevational view, and

Figure 5 is a sectional elevation on line 5—5 of Figure 1.

I claim:

The ornamental design for a step box, substantially as shown.

THOMAS C. BAIR.
